(57) **CLAIM**

The ornamental design for a packaging for cosmetic products, as shown and described.

DESCRIPTION

FIG. 1 is a front perspective view illustrating my design for a packaging for cosmetic products showing an outer container and seven identical pouches disposed therein.

FIG. 2 is a rear perspective view thereof.

FIG. 3 is a front view thereof.

FIG. 4 is a rear view thereof.

FIG. 5 is a left-side view thereof.

FIG. 6 is a right-side view thereof.

FIG. 7 is a top view thereof.

FIG. 8 is a bottom view.

FIG. 9 is a front perspective view of one of the pouches of the packaging for cosmetic products in FIGS. 1-8 shown by itself for clarity of illustration.

FIG. 10 is a rear perspective view thereof.

FIG. 11 is a rear view thereof.

FIG. 12 is a front view thereof.

FIG. 13 is a top view thereof.

FIG. 14 is a bottom view thereof.

FIG. 15 is a right-side view thereof; and,

FIG. 16 is a left side view thereof.
